US0D1055785S

(12) **United States Design Patent** (10) **Patent No.:** **US D1,055,785 S**
(45) **Date of Patent:** **** Dec. 31, 2024**

(54) **BREAK ACTUATOR**

(71) Applicant: **Stryker Corporation**, Kalamazoo, MI (US)

(72) Inventor: **Cory P. Herbst**, Shelbyville, MI (US)

(73) Assignee: **Stryker Corporation**, Portage, MI (US)

(**) Term: **15 Years**

(21) Appl. No.: **29/790,995**

(22) Filed: **Dec. 23, 2021**

(51) **LOC (14) Cl.** **12-12**

(52) **U.S. Cl.**

USPC **D12/133**

(58) **Field of Classification Search**

USPC D12/128, 131, 133

CPC A61G 5/04; A61G 5/041-047; A61G 2005/048; A61G 5/00-14

(57) **CLAIM**

The ornamental design for a break actuator, as shown and described.

DESCRIPTION

FIG. 1 is a front, right-side, perspective view of a break actuator;

FIG. 2 is a top view thereof;

FIG. 3 is a bottom view thereof;

FIG. 4 is a back view thereof;

FIG. 5 is a front view thereof;

FIG. 6 is a right-side view thereof; and,

FIG. 7 is a left-side view thereof.

The broken lines in the drawings depict portions of the break actuator that form no part of the claimed design.
